Des. 175,299
Patented Aug. 9, 1955

175,299

HOSIERY PACKAGE

William De Mond, Los Angeles, Calif.

Application November 9, 1954, Serial No. 33,042

Term of patent 14 years

(Cl. D58—12)

FIG. 1.

FIG. 2.

FIG. 3.

Fig. 1 is a top plan view of a hosiery package, showing my new design.

Fig. 2 is an elevational view of the side of Fig. 1 extending along the lower edge of that figure, and

Fig. 3 is an elevational view of the left hand end of Fig. 1.

I claim:

The ornamental design for a hosiery package, substantially as shown.
